SORTING MACHINE

Paul Mansel, Berlin-Lankwitz, Germany, assignor to Siemens & Halske Aktiengesellschaft, Siemensstadt, near Berlin, Germany, a corporation of Germany

Application June 12, 1937, Serial No. 147,884
In Germany June 29, 1936

8 Claims. (Cl. 209—110)

This invention relates to a punched card sorter and more particularly to the type of sorter having spring metal blades acting as chutes to the pockets and which is adapted to sort perforated cards perforated in one or more codes.

Sorters of this type heretofore have been built to sense only one code, such as a single hole or 45 column code, or a double hole or 90 column code. Also sorters of this type usually have the chute 10 blades arranged in a single group one above the other.

It is, therefore, the principal object of this invention to provide a sorter in which the chute blades are arranged in a plurality of groups in 15 side by side relation.

A further object is to provide a novel form of control for the chute blades comprising a series of permutation bars which are adapted to select the particular pocket to which the card is to be 20 routed.

Another object is to provide a translator which is adapted to sense either single or double hole codes and translate the data to control the operation of the machine by the use of permutation 25 bars.

A still further object is to provide a sorter which is accurate, efficient and capable of sorting cards at a high rate of speed.

A more clear conception of the construction, 30 operation and further objects of the invention may be had from the following specification taken in conjunction with the accompanying drawings in which:

Fig. 1 is a longitudinal section of the machine showing the principal operating parts;

Fig. 2 is a continuation of Fig. 1 disclosing the pockets and chute blade mountings;

Fig. 3 is a plan view of the machine with the sensing head removed and portions of the controls cut away;

Fig. 4 is an enlarged detail of the left side of the machine showing the main drive shaft with the sensing head in raised position;

Fig. 5 is similar to Fig. 4 disclosing the right hand side of the sensing head, which is shown in lowered position;

Fig. 6 is a detail side elevation of the sensing pin carriage;

Fig. 7 is a cross section through line 7—7 of Fig. 6;

Fig. 8 is a detail section through line 8—8 of Fig. 6;

Fig. 9 is a front view of the sensing pin carriage;

Fig. 10 is a detail of the control drum for the sensing pins;

Fig. 11 discloses the main drive shaft with its associated cams and gears for controlling the operation of the machine.

Fig. 11A discloses the card sequence sensing pin cam;

Fig. 11B discloses the card stop cam;

Fig. 11C discloses a feed roll and the card picker cam;

Fig. 11D discloses one of the selector blade operating cams;

Fig. 11E discloses the sensing pin operating cam;

Fig. 12 discloses the sensing head in rear elevation together with the controls and sensing pin operating ball;

Fig. 13 is a plan view of the translator;

Fig. 14 is a cross section through line 14—14 of Fig. 13;

Fig. 15 is a rear elevation of the translator mechanism showing the chute blade selecting pins;

Fig. 16 is a plan view of the section of the translator containing the permutation bars and their associated electro-magnetic locking members;

Fig. 17 is a cross section through line 17—17 of Fig. 16;

Fig. 18 is a detail showing of the connecting plug for the sensing pin carriage;

Fig. 19 is a schematic representation of the permutation bars and their associated magnetic locks and the chute blades controlled thereby;

Fig. 20 is a cross section through line 20—20 of Fig. 1;

Fig. 21 is a detail cross sectional view of a mounting for the chute blades and the associated parts;

Fig. 22 is an isometric showing of a group of chute blade tips disclosing the control holes;

Fig. 23 is a detail of the device for preventing overloading of the pockets;

Fig. 24 shows a portion of a 45-column card containing data perforated in the single hole code;

Fig. 25 shows a portion of a 90-column card containing data in the two-hole code;

Fig. 26 is a schematic wiring diagram of the operating circuits for the sorter;

Fig. 27 is a timing chart of the different essential operations of the machine.

In operating the machine the sensing pin carriage, containing the sensing pins is positioned above the particular columns which are to be sorted. The switch corresponding to the digit or 55

digits to be sorted to is operated and then the start switch is operated.

The cards are fed individually from a card magazine, by a card picker, to a pair of feed rolls, 5 thence into a sensing chamber where they are held by a card stop. When the card reaches the sensing chamber the pins descend and sense the data by means of which the desired pocket is selected. The card is then fed by feed rolls up 10 to and between the chute blades which have been selected by the sensed data. These blades have been set up by the data which controls magnetic locking members which, in turn, control permutation bars. These permutation bars 15 are so positioned as to permit only one blade operating pin to rise thereby opening a path between the blades to the selected pocket.

The chute blades start directly behind the sensing chamber and extend in four groups of 20 three blades positioned one above the other, to form horizontal guiding surfaces between the feed rolls and below which the sorting pockets are arranged in series. When the card leaves the sensing chamber, it is carried in between the selected blades, which have been raised and the next lower set of blades which remain normal, and is carried by the chutes formed of the blades and the feed rolls, until it reaches the end of the chute blades. The ends are bent down to 25 carry the card away from the next pair of feed rolls and into the selected pocket. The front end of the chute blades are formed with rigid tips, whereas the remainder of the blades are of spring material. The tips are raised by selecting pins 30 which are operated by cam actuated levers under control of the permutation bars. The permutation bars are spring operated, and are controlled in their movement by magnetically operated latches. The magnets controlling the latches are 35 controlled in turn by contacts closed by the sensing pins under control of the sensed data. Between the contacts and the electromagnets a switch is used to select whether the card shall be sorted to 45-column or 90-column code.

45 Card magazine and main drive

The machine is formed as best shown in Figs. 1, 2 and 3 and comprises a table-like structure 5, 50 which is supported by legs 6. Secured to each end of the table is an end frame member 7 to which are secured side frames 10 and 11 adapted to carry the operating mechanism of the machine. Carried on a shelf 12, suspended from table 5 by arms 13, is a motor 18.

55 The frame members 10 and 11 are connected together over each pocket by a cross bar 14 and at the front end by the base member 15 of the card magazine.

Secured to the base member 15 is a card magazine 20 below which is located a card picker 21 of a well known type adapted to carry a card from the magazine into the feed rolls 22, which, in turn, carry it into the sensing chamber formed of a perforated plate 19 and a second similar plate 23 secured to the sensing head. These plates are provided with forty-five columns or rows of twelve holes each.

The card picker is provided with webs 24 to 70 which are secured horizontal studs 25 on which are pivoted eccentric strap bars 26. The bars 26 cooperate with eccentrics 27 (Figs. 11 and 11C) mounted on the main drive shaft 30 which reciprocate the picker in a well known manner.

The main drive shaft is journaled in ball bearings 31 (Figs. 3 and 11) secured to the side frames

10 and 11. Fastened to the right hand end of shaft 30 is a pulley wheel 32 which is connected by a belt 33 to a smaller pulley on the drive shaft of the motor 18. Secured to the other end of the drive shaft 30 is a hand wheel 34 to permit manual operation of the machine. Adjacent to the hand wheel and outside of the frame 10 is a gear wheel 35 (Figs. 3 and 4) with which mesh idler gears 36, which, in turn, mesh with gears 37 and 38 secured to the shafts 40 and 41 of the 10 feed rolls 22 and eject rolls 39.

5 Mounted above and parallel to shafts 40 and 41 are spring pressed shafts 42 and 43 carrying pressure rolls 44 and 45. The rolls 45 cooperate with feed rolls 22 to carry the card into the sensing chamber and the rolls 44 cooperate with eject rolls 39 to carry the card out of the sensing chamber and in between the chute blades.

15 Secured to the drive shaft 30 (Figs. 3, 11, and 11C) on each side of the sensing chamber are feed rolls 48 to which are secured the eccentrics 27 referred to above. The feed rolls 48 extend through slots in the bottom plate 19 of the sensing chamber. Secured to the plate 23 on each side of the perforated portion is a stud on which 20 is pivoted a spring operated arm similar to those carrying shafts 42 and 43. The arm carries a stud on which is mounted a pressure roller 50 (Fig. 1) and a gear 51. The gear 51 meshes with 25 and is driven by a gear 52 secured to the drive 30 shaft 30, thereby insuring a positive drive for both of the rolls.

30 A card stop 60 is provided to hold the card in the sensing position and prevent the rolls 48 and 50 from carrying it out of the sensing chamber. 35 The card stop comprises two fingers, each of which is mounted on an arm 61, carried on a shaft 62 journaled in the side frames. Secured between the fingers is a bar 60. The lower edges of arms 61 are spring pressed against cams 63 40 (Fig. 11B) secured to the drive shaft 30, thereby controlling the raising of the card stop into the path of the card at the required time.

45 After the card leaves the sensing chamber under control of eject feed rolls 44 and 48, it passes in between the chute blades leading to the separate pockets where it is picked up by the feed rolls 65 and the pressure rolls 66. A pair of these rolls is provided for each of the pockets. These rolls are driven by a gear train comprising 50 gear 35 secured to the main drive shaft, idler gear 36, gear 38 through shaft 41 to which gear 38 is secured, to gear 70 secured to the other end of shaft 41, idler gears 71 (Figs. 3 and 5), and gear 72 secured to shaft 73 on which is secured 55 feed rolls 65. A shaft 74 mounted directly above shaft 73 carries pressure rolls 66. An idler gear 76, meshing with the gear 72 (Fig. 5), drives the gear 72 of the next adjacent pair of rolls. In this manner the feed rolls 65 are driven continuously by the main drive shaft.

Sensing head

The sensing head contains a carriage in which are movably mounted a single row of thirteen 65 vertical pins each of which is adapted to close a bank of electrical contacts when in its lowermost position. The carriage (Fig. 12) is mounted on a frame which permits the adjustment of the sensing pins over any desired column of the 70 card. The frame comprises two side members 80 and 81 which are secured together at the top by a cross bar 82 and further connected together by rods 83 (Figs. 4, 5, and 12). Secured to the rear vertical edge of members 80 and 81 are plates 75

84 and 85 to the bottoms of which is secured a plate 23 having 45 rows of twelve holes each therein corresponding to the positions of the perforations in a card.

5 Secured to each of the side members 80 and 81 is a hook shaped arm 87 which engages a stud 88 projecting from each of the side frames 10 and 11. The hook members provide pivots about which the entire sensing head frame may be rotated, as shown in Fig. 4, to permit adjustment of the pins and replacement of the translator. The entire head may be easily removed by unhooking the arms from the studs. It is held in the raised position by a toggle link comprising 15 two arms 89 and 90, pivoted together and secured to the member 80 and the frame piece 10. In the lowered position a hook-shaped latch member 91 on each side of the frame engages a stud 92 secured in the frames 10 and 11, thereby locking 20 the frame in its lowered or operative position. The latches are held in their operative position by springs 93.

The sensing pin carriage comprises an inverted U-shaped casting 100, formed as shown in Figs. 25 6 to 9 inclusive, having holes 101 therein for accommodating the tie rods 83. The carriage is supported for lateral movement on these rods thereby permitting it to be positioned over any desired column of the card. Journalized in the 30 side members 80 and 81 is a shaft 102 having a screw thread cut therein which is adapted to cooperate with a thread 103 tapped in the casting 100 (Fig. 7). Attached to one end of shaft 102 is a crank 104 by means of which the shaft may 35 be rotated, thus driving the pin carriage laterally to a position over the desired column. An indicator 105 secured to the frame 100 cooperates with a scale (not shown), on bar 82 whereby the columns may be identified. To insure that the 40 carriage will be positioned with the pins in alignment with the holes in the plate 23, thus obviating the damage of both pins and cards, a notched disc, described hereinafter, is secured to the shaft 102 at the end opposite to that of the crank.

45 A horizontal shaft 107 is journaled in the casting 100 and has rotatably mounted thereon thirteen three-armed levers 108 formed as shown in Figs. 7 and 8. The rearwardly (to the left in Fig. 7) extending arm 109 of each lever is pivotally connected to the bifurcated head of a sensing pin 110, as shown in Fig. 6. A comb 111 fastened to the casting 100 serves as a vertical guide for each of the sensing pins 110 and the lever 108 as well as a point of fastening for the springs 50 112 which tend to draw the pins downward. The levers 108 are provided with downwardly extending arms 113 formed as shown in Fig. 7 with a forwardly extending finger of insulating material such as hard rubber or Bakelite. Each of 55 these fingers is adapted to close the contacts of a bank of contact springs 114 which is mounted on the casting 100 as shown.

60 Adjacent the pivot point of the lever 108 is an upwardly extending finger 115 which is adapted to engage slots 109 and 118 cut in a drum 116 journaled in the casting 100. The drum is manually rotated by a hand lever 117. The drum 116 is provided with slots 109 cut in the surface as 65 shown in Figs. 7 and 10, two of which are separated by a few degrees of rotation and extend in opposite directions from the middle of the shaft, and the third, 118 still further angularly displaced, extends the full length of the shaft. These slots are provided to lock out or prevent 70 the operation of certain of the sensing pins 110

under certain conditions. If it is desired to sense a 45-column card, in which all twelve such positions are used, as shown in the card in Fig. 25, then the hand lever 117 is positioned so that the full length slot 118 is in line with the fingers 115. If, however, it is desired to sense a 90-column card, which is divided in two zones, each using only six positions, then the lever 117 is positioned to permit only six of the fingers 115 free movement in either of the slots 109 and thus lock 10 out or prevent the complete swing of the other six. A pointer 119 is provided on lever 117 which moves over a scale 120 to indicate the adjusted position of shaft 116.

75 A universal ball 125 is carried by link 126 pivoted on one end of the shaft 107 and a T-shaped lever 127 pivoted on the other end thereof. The upper arm (Figs. 7, 8 and 12) of the lever 127 carries a stud 128 on which is pivoted a roller 130. The roller is adapted to ride on the upper edge 20 of a horizontal bar 131 (Fig. 12) which is mounted for parallel movement between rollers 132 mounted on plates 84 and 85. With the bar 131 in normal position the universal ball 125 contacts all of the levers 108 holding them in the position shown 25 in Fig. 7 thereby holding the pins 110 in their elevated position against the action of the springs 112. In their elevated position the pins are above plate 86 leaving the sensing chamber clear for the entrance of a card. When the bar 131 moves 30 down, roller 130 follows the movement, thereby rotating the universal ball 125 in a counter-clockwise direction, permitting all of the pins, not prevented from doing so by drum 116, to descend and sense the card in the chamber. Such pins 35 as find perforations in the card descend the maximum distance bringing the finger 113 into engagement with the contacts 114. The pins finding no perforations will descend only part way which distance is not sufficient to engage the contacts. 40 A pin 129 (Figs. 6 and 8) is provided which is shorter than pins 110 and, therefore, does not contact the card. Secured to pin 129 by a block 132 is a pin 133 adapted to contact the card between punching positions. A special hole located 45 between perforation positions, is provided in plate 86 to accommodate this pin. Pin 133 senses the presence of a card in the sensing chamber and is only operative when a card fails to enter the chamber due to some reason. At that time the 50 pin is free to descend and opens contacts 134, stopping the machine.

The wires connecting the sensing contacts 114 and the card presence contacts 134 with the controls in the base of the machine are carried in a 55 flexible metal tube 135, which ends in a multi-contact plug 136 (Fig. 18) which has two rows of contact fingers 137 adapted to be inserted in jacks provided in the base at 138 (Fig. 1). This permits the sensing head to be easily and quickly removed and replaced without the necessity of disconnecting a number of wires from a terminal board.

The horizontal bar 131 (Fig. 12), referred to above, is mounted for parallel vertical reciprocating movement with respect to the pin carriage. The bar extends horizontally across the entire length of the sensing chamber and has its ends bent at an angle as shown to pass between rollers 132. The bar is spring urged toward the 70 right (Fig. 12) by a spring 139, and is raised against the action of the spring by an arm 140 which has a right angle lug formed thereon acting in a slot 141 in the left hand end of bar 131. The arm 140 is L shaped (Fig. 12) and is se- 75

cured to a sleeve 142 loosely mounted on a stud 143 secured between plates 85 and 124. Also secured in and extending at right angles to the sleeve 142 is a stud shaft 144 on which is carried a roller 145 adapted to cooperate with the cam 146 (Fig. 11E). A high spot on cam 146 will raise the bar 131 through the rotation of arm 140 in an anti-clockwise direction (Fig. 12) and the spring 139 will cause the roller 145 to follow the cam until a low spot is reached and the bar is lowered, thereby lowering the sensing pins 110 and 133 into contact with the card. The cam 146 causes the release of the sensing pins once each cycle.

To prevent the damage of cards and sensing pins by the incorrect positioning of the pin carriage through the medium of the crank 104, as described above, the end of shaft 102 (Fig. 5) opposite to the crank is provided with a notched disc 149 with which a catch pawl 150 is adapted to cooperate. The disc 149 is so positioned on the shaft that the pawl may enter the notch only when the pins 110 are positioned in alignment with the holes in plate 86. The lower end of pawl 150 is extended into the path of an arm 151 secured to the sleeve 142. When the bar 131 is lowered by the clockwise rotation of sleeve 142 to permit the pins to descend, the arm 151 will move into the path of the lower end of the pawl, thereby preventing its leaving the notch in the disc and thus locking the handle 104 from rotation and the consequent movement of the pin carriage. Conversely, the pins cannot be lowered while the pins are out of alignment with the holes in plate 86 as the pawl 150 will be out of the notch in disc 149 and then rocked into the path of arm 151 thereby preventing rotation of sleeve 142.

Translator

The translator is a removable unitary structure positioned directly below the sensing head and comprises a set of permutation bars and magnets for controlling the bars and associated chute blade setting pins. These parts are carried on two horizontal plates 155 and 157 (Figs. 14 and 15) which are secured together by stay bolts 156. The sides of the plate 155 are bent up to form vertical side pieces 158 in which holes 159 are provided through which a bolt 160 is adapted to pass into the side frames 10 and 11 to fasten the translator to the machine. The front end of the members 158 are formed with finger pieces 161, while the rear ends are formed with a sloping cam face 162 as shown in Fig. 14. This face is adapted to cooperate with a spring urged latch member 163 (Fig. 1) pivoted at 164 and having a roller 165 thereon, which is adapted to hold the translator in its adjusted position in the machine. To place the translator in the machine the holes 159 are aligned with holes in the frame and the bolts 160 are then fastened to form a pivot about which the translator is swung upwardly until the cam face 162 engages a roller 165 on the latch member 163 rotating the latch in a clockwise direction out of the path of the member 158. When the member 158 has passed, the latch snaps back into position, placing the horizontal arm and roller under the edge of the member 158, thus holding the translator in its operative position.

An auxiliary frame member 168 (Figs. 16 and 17) is secured to the plate 157 by bolts 169 on which are positioned rollers 165. Positioned for lateral movement between the rollers is a group

of permutation bars 170-177. These bars are formed as shown in Fig. 19 with the number of teeth 178 on the front edge and a series of notches 179 on the rear edge thereof. The bars are held in spaced relation in their mid position by a comb shaped block 180 and their ends by spacers 181 straddling the bolts 169. Secured to the right hand of each of the bars is an arm 182 to which in turn is secured a spring 183 which is anchored to the plate 184 and stud 187.

Secured to the plate 157 is a comb plate 197, the teeth of which extend below the permutation bars and form guide grooves for the arms 185 of the chute operating levers 186. The teeth 178 on the permutation bars are adapted to form blocking members or stops for the grooves to limit the movement of the arms 185. The teeth are so arranged that, when the permutation bars have been positioned in accordance with data sensed from the cards as will be described hereinafter, there will be one or more grooves or spaces into which the arms 185 may enter. There are two sets of similar teeth on each bar (Fig. 19) one set to the right of the center block 180 and the other to the left. The two sets of similar teeth are provided due to the fact that there are two chute blades to each pocket therefore the levers 186 must act in pairs to control the chute positioning pins. As will be seen in Fig. 19, the number of teeth are in accordance with the digits 30 13-11-10-8-6-4-3-2. The notches 179 are provided to act as stops with which magnetically operated latches 190-196 may engage. In actual operation only one of these notches is necessary to each bar, but, to simplify the manufacture, all bars are made the same. Near the center of each bar a hollowed notch 188 is provided with which a restoring pawl 189 is adapted to cooperate for restoring all of the bars at once.

In their normal position, the permutation bars 40 are held against the action of springs 183 by the latch members 190-196. The restoring pawl moves all of the bars into engagement with the latches, once every cycle, where they are held until released by the operation of one or more 45 of the magnets. Since the magnets are operated during the time the bars are being held restored by the pawl 189, the released permutation bars follow the pawl until the teeth reach their selected positions. The normal position of teeth 178 is 50 shown in Fig. 16.

Latches 190-196 are each adapted to hold only one permutation bar in its normal position. Latch 190 however has an additional function in that it acts as a limit stop for all bars except 55 bars 171 and 176. Referring to Figs. 17 and 19 it will be noted that latch 190 is of a different formation than the other latches in that it presents a broad face 198 which constitutes a limit stop to the slides 172-175 and 177 and has a finger 167 which cooperates with the bar 171, when in its normal position. All of the permutation bars are individually controlled by a latch except bar 170. All of the bars except 170, 171 and 176 are adapted to be stopped in partial travel by the 60 limit 198.

The extent of travel of each of the individual permutation bars may vary. The full travel is limited by block 180, which is formed with steps as shown in Fig. 19. Each of the permutation 70 bars is provided with a stop 199 which is adapted to limit on one of the steps of the block 180. The block 180 is secured between the plates 157 to 168. Permutation bars 171 to 175 (Fig. 19) have the greatest extent of travel, with respect 75

to block 180. Slides 170 and 177 may travel two-thirds of this distance only, and slide 176 one-third. Permutation bars 170 and 171 are provided with additional stops which are adjustable.

5 These stops comprise metal blocks 200 and 201 pivotally mounted on studs anchored in the frame plates 157 and 168. Block 200 is formed as shown with a stop shoulder 202 and the block 201 is formed with an incline cam face 203. Secured 10 to the block 200 is a sheet metal member formed with an arm 204 and a stop lug 205. A second sheet metal member having an arm 206 and a stop 207 is secured to block 201. The arms 204 and 206 (Fig. 16) are connected by a spring 208 which tends to rotate the blocks and stops toward one another.

It will be noted that the ends of the permutation bar opposite from the arms 182 are ground to form an incline face 209 which cooperates with 20 the face 203 to rotate the block 201 in a clockwise direction. The ends of the bars are adapted to cooperate with the shoulder 202 on block 200 tending to rotate it in a clockwise direction. Also the bars are formed with shoulders 210 and 211 which are adapted to contact stops 205 and 207. The spring 208 tends to hold stop 205 out of the path of shoulder 210 and stop 207 into the path of shoulder 211. The shoulders on bars 170 and 171 are the only ones effective but for simplicity 25 of manufacture the bars are all stamped the same. As shown in Fig. 19, the lower end of permutation bar 170 has been cut off and the lower end of bar 171 has been ground off so that bar 170 is unable to contact either block 200 or 201 and 30 bar 171 will not be able to rotate block 200. When one of the bars 172 to 177 has been released by its magnetic pawl, the end of the bar rotates block 201 in a clockwise direction and removes the stop 207 out of the path of shoulder 211 on 35 bar 170, thereby permitting its movement. At the same time the end of the operative bar contacts shoulder 202 rotating the stop 205 into the path of shoulder 210 on slide 171 preventing its movement. It is therefore apparent that the 40 movement of bars 170 and 171 is controlled in part by the bars 172-177. The only time that bar 171 travels its full distance is when latch 190 is operated alone.

The restoring pawl 189 (Figs. 16 and 17) is 45 formed of corrugated metal so that it has a limited amount of resiliency and is pivoted on a block 215 (Figs. 14 and 16). The rear edge of the stop 189 is formed with a lug 216, which is resiliently connected by a spring to a stud 217. 50 The block 215 is mounted on an eccentric shaft 218, which is fastened at its lower end in the plate 157 and in its upper end to a bracket 219 secured to the upper face of the plate 155. The shaft 218 is made eccentric to permit longitudinal 55 adjustment of block 215 with regard to its pivot point. The stud 217 extends through block 215 and a cam roller 220 is mounted thereon which is adapted to cooperate with a hat shaped cam 214 on the main shaft 30 (see Fig. 11). The block 60 215 is connected by a spring extending from stud 217 to a pin 221 fixed to plate 168 which tends to rotate the block in a clockwise direction, thereby holding cam roller 220 in engagement with its associated cam. The cam 214 is formed with 65 a rise which causes block 215 to rotate in a counter-clockwise direction once during each cycle of the machine, thereby bringing pawl 189 into engagement with notches 188 in the permutation bars and restoring them to normal. After the 70 75 rise in the cam has been passed, the bars, whose

latches have been released, follow the restoring bar and the remaining bars are held in their normal position by the magnetically operated latches. Secured to the left side (Fig. 16) of block 215 and extending downwardly, is an arm 222 of spring 5 metal (Fig. 14) which passes through a slot cut in the plate 157, to engage the electric contacts 223. These contacts are held open when the block 215 is in its normal position (i. e., with the roller on the low portion of the cam). During the restoring and subsequent setting of the permutation bars, however, this contact is closed.

Secured between and in the frame plates 157 and 168 are a series of pivots 224 on which are pivotally mounted the pawls 190-196, inclusive. 15 Secured to the upper end of the pawls is an arm 225 carrying a pin, which is adapted to cooperate with a fork formed in the end of an arm 226. An arm 226 is secured to each of the armatures of the control magnets in such a manner that 20 when a magnet is operated the arm 226 (Fig. 16) is rotated in a clockwise direction, thereby rotating the arm 225 in a counter-clockwise direction to withdraw its individual holding pawl from contact with the notch 179 in its associated permutation bar or bars.

Central switch stand

Secured to the upper surface of plate 155 are 30 three journals 227 in which is carried a shaft 228. Pivotal mounted on shaft 228 and separated by spacers are two sets of thirteen L-shaped levers 186. The downwardly extending portion 185 of levers 186 is adapted to enter the 35 guide grooves formed by the comb 168 and controlled by the permutation bars 170-177. Pivotally mounted on the horizontal portion of each of the levers 186 is a cam roller 230 adapted to cooperate with a series of cams 231 (Fig. 11A) secured to the drive shaft 30. The 40 bars 186 are positioned on the shaft 226 in groups of three and secured to the extreme end of the horizontal portion of each is a finger piece 232, 233 or 234.

These finger pieces are offset and of different 45 lengths as shown in Fig. 14 and are adopted to individually control the chute blades 240 to 249 inclusive. The ends of the blades are provided with non-resilient tips 239 which are positioned in eight groups of three, a typical group 50 being illustrated in Fig. 22. The tip of blade 242 or the lowermost tip of any group is provided as shown with an L-shaped slot 235. The offset finger 232 is adapted to pass through the outer portion of slot 235 and raise blade 241. The finger 233 is adapted to contact and raise blade 242 and finger 234 passes through the inner portion of slot 235 and slot 236 in the tip of blade 241 to contact and raise blade 240. The contact 55 points are indicated by dotted rectangles on each blade and are designated by the same character as the contacting finger.

Secured to the lower end of each arm 185 is a 60 spring 237 which is anchored on a cross shaft 238. The spring tends to rotate the arm 186 65 with its associated roller up into engagement with the cam 231. The shafts 238 are staggered to accommodate the springs in the least amount of space.

This machine is provided with a special sensing finger 264 which is shaped as shown in Fig. 14 and with it a test is made to determine whether the cards are being fed in correct relation or not. The finger 264 is loosely mounted 70 on a stud carried by a link 265 pivotally mounted 75

on a bar 253, positioned near the center of the machine. This bar is mounted on the shaft 228 and has a cam roller 254 adapted to cooperate with a cam 255 (Fig. 11A). The forward end 5 of finger 264 is pivotally connected to an arm 256 having a foot 257 (Figs. 14 and 15) formed on the lower end thereof which cooperates with a T-shaped lever 258, which is adapted to open and close the contact 259. Secured by pin and 10 slot connection to the downward extending portion of lever 258 is a slide 260, which is adapted to cooperate with an L-shaped arm 261 (Figs. 1 and 23), secured to a shaft 262 running the length of the machine, just below the card pockets. Secured to the shaft 262 and individual to 15 each card pocket is an arm 263 which is adapted to be operated when the card pocket or pockets are filled. The operation of arm 263 causes the rotation of shaft 262, thereby rotating arm 261 into contact with slide 260. This operation causes the rotation of arm 258 in a counterclockwise direction, thus opening the contacts 259 which will stop the machine.

The lever 253 has a cam roller 254, which is 20 adapted to cooperate with cam 255 (Figs. 11 and 11A). Once every cycle of the machine, the arm 253 is raised at such a time, that if the cards are being correctly fed, the free end of sensing finger 264 will pass between two cards. If, however, there is any interruption in the feed, or 25 the cards are not fed in their correct spacing, the free end of finger 264 will strike a card, thereby causing the arm 256 to be raised due to the counterclockwise rotation of finger 264 about its pivot in link 265. The raising of arm 256 causes the rotation of T-shaped lever 258, thereby 30 opening the contacts 259 and stopping the machine.

40 Sorting pockets and chute plates

The machine is provided with thirteen pockets 280 to 292 inclusive as shown in Figs. 2 and 19. These pockets are formed in a manner well known in the Powers type of machine and are 45 provided with a slanting plate carried on a guiding hub for receiving and stacking the cards. Extending from a point to the rear of the sensing head to each of the pockets is a pair of chute blades such as 240 to 252 inclusive (see Fig. 19).

Above each card pocket is secured a cross bar 269 to the bottom of which is secured a U-shaped member 270. The extreme ends of the chute blades are secured to the member 270 as shown in Fig. 21. Also secured to the mid portion of 55 member 270 is a spring plate 271 which acts as a deflector for the card entering the pocket. Secured to the upper face of bar 269 is a V-shaped member 272 which acts as a support and guide for the chute blades to the adjacent pockets and also as an additional deflector at each 60 end of the card entering the pocket. The side frames 10 and 11 are provided with slots located one above each pocket in which are positioned arms 273 formed as shown in Fig. 21 to the bottom of which is secured a bar 274 which extends across the machine and is spring 65 pressed at its end by a U-shaped spring 275 which is secured to the underside of cross bar 269.

70 The chute blades are arranged in groups of three positioned one above the other, there being two blades for each pocket, one extending along the right hand side of the machine and the other extending along the left hand side of 75 the machine. There are four groups of blades

for each side of the machine, as shown in Figs. 19 and 20, and they extend to the pockets in the following order. Chute blade 250 to the first pocket 280, chute 251 to the second pocket 281 and so forth through to chute blade 252 which extends to the last or reject pocket 292. It is obvious that the cards which are rejected do not contain data in the column being sensed and therefore none of the permutation bars will be released and none of the blade setting fingers 10 will be raised. This necessitates that the blades 252 be on the top and that they be elevated into the path of the cards at all times. When a card is to be routed to the next or "9" pocket, only 15 one set of blades is elevated, whereas when a card is to be routed to the "12" pocket all of the chute blades must be elevated.

The extensions 239 of the chute blades are positioned in slots formed in the rear edge of a plate 276, over which the card is adapted to travel. When the blades are raised they come 20 above the plate 276 and the card, therefore, passes between the plate and the under edge of the chute blade. It is then picked up by the feed rolls 65 and carried between the elevated 25 blade and the next lower blade until the pocket at which the raised blade ends is reached. At this time it is forced down by the blades until it strikes plate 272 and deflector 271, whereupon it drops into the selected pocket.

The extensions of the chute blades 250 which 30 extend to the reject pocket are always elevated into the path of the card so that it is not necessary that a blade operating finger such as 232 be operated. If a card is found which does not 35 cause the operation of a finger it passes directly 40 from the sensing chamber under the chute blades 250 to the reject pocket.

Mechanical operation

Fig. 19 is provided to show schematically the 45 location and position of the sorting pockets, chute blades and permutation bars. The permutation bars are actually located one above the other but for clearness they are shown one alongside the other. The latch pawls, together with the stop members 180, 205 and 207 are shown with their associated permutation bars in their normal or inoperative position. The horizontal dotted lines mark the path of the arms 185 50 which, when released by the cams 231 are adapted to enter between the teeth 178 of the bars. The chute blades 240-252 are shown ending over their respective card pockets to which the blades lead. As shown in the drawings the chute 55 blades are in reverse with regard to their true location, i. e., the blade 240 which ends at pocket 280 is located below blades 241 and 242 and not above as shown. The blades are drawn in this manner to more clearly disclose the mechanism. 60

In order to describe the operation of the mechanical parts of the machine an example will be given in which a card containing the digit "6" is to be routed to the correct pocket, i. e., 65 288. As the decoding of the separate codes is done electrically, this feature will be explained hereinafter under discussion of the circuits.

A "6" in the 45-column card 293 (Fig. 24) is 70 designated by the hole 294, which will cause the fourth pin from the right (Fig. 6) to descend when the pin box is lowered, thereby closing a contact 114 which, in turn, completes a circuit to one or more of the electro-magnets 300 and 305 (Fig. 16) which operate to release latches 190 and 195, thereby releasing slides 170, 171 and 75

173. The bar 173 travels under control of the restoring arm 215 until the face 209 contacts block 201, rotating it and its associated stop 207 out of the path of slide 170, permitting it free movement into an active position, i. e., with the teeth out of the path of arms 185. The foot of bar 173 also contacts block 200, rotating it in a clockwise direction to interpose stop 205 in the path of shoulder 210 on bar 171, thereby preventing it from completing a full travel and thus stopping with its teeth out of the path of the arms 185. The bar 173 having been released by both latches 190 and 195 will travel until the lug 199 limits on the block 180. In this position the teeth of bar 173 are in blocking position for all arms 185 except those controlling blades 248-251, inclusive. These blades will be elevated and the card will pass from the eject rolls 48 and 50 to the feed rolls 38 and 44 and thence between blades 247 and 248 to the "6" pocket. If a "1" is sensed, magnet 303 will be operated, thereby removing latch 193 from the path of bar 175. The bar will travel until notch 179 contacts the broad face 198 of the pawl 190. In this position the teeth 178 will block the arms 185 associated with the blades 240 to 242, inclusive, thereby preventing them from being raised. The bar 170 is released in the same manner described above and comes to rest with its teeth clear of the arms 185. The card will pass between blades 242 and 243 and enter the "1" pocket.

The following table will clearly show the magnets and latches which are operated to position the permutation bars for raising certain chute blades for routing cards to the different pockets.

0	Digit sensed	Pocket	Magnets operated	Permutation bars		Chute blades
				Part travel	Full travel	
9		291	300	171	170, 171	251
8		290	300, 306	171	170, 172	251, 250
7		289	306	172	170	251-249
45	6	288	300, 305	171	170, 173	251-248
5		287	305	173	170	251-247
4		286	300, 304	171	170, 174	251-246
3		285	304	174	170	251-245
2		284	300, 303	171	170, 175	251-244
1		283	303	175	170	251-243
0		282	302	176	170, 176	251-242
50	11	281	301	177	170	251-241
12		280	300, 301	171	170, 177	251-240
Reject		292		170		252

It will be noted in the above table that permutation bar 170 travels the full distance between its restored position as indicated in Fig. 19 and the position in which lug 199 contacts bar 180 in all cases except that of rejected cards, at which time it only travels a portion of the maximum, i. e., until the shoulder 211 contacts stop 207. This is the theoretical action, actually the shoulder 211 contacts stop 207 immediately the cam 214 permits the restoring pawl 189 to return to normal. In this position the teeth 178 will be interposed in the path of cams 185.

Code switch

It will be noted in the above table that certain of the magnets 300-306 are operated sometimes singly and sometimes in pairs for different digits. This is due to different code combinations as the machine is adapted to sense cards perforated in a two hole 90-column code or in a single hole 45-column code. In Fig. 24 a portion of a card 293 is shown perforated in the 45-column code.

In Fig. 25 a portion of a card 296 is shown perforated in the two hole 90-column code.

The code switch 310 (Fig. 1) comprises a shaft having a plurality of fingers thereon for opening one set of contacts and closing another as shown in Fig. 26. In one position circuits are closed for connecting magnets 300-306 to the contacts 114 over one set of circuits in accordance with the 45-column code and in the other position the magnets are connected to the sensing contacts over a second set of circuits in accordance with the 90-column code. No showing other than the schematic in Fig. 26 has been made as multi-contact switches of this type are well known.

Operating circuits

The operating circuits of the machine are shown in Fig. 26. A series of contacts enclosed by a dotted line box at the top of the diagram correspond to the contacts 114 and 134 in the sensing pin carriage. The conductors from these contacts pass through the fingers of plug 136 to a series of individual contacts controlled by push buttons 312 located toward the front on the left side of the machine. These push buttons are used to select which of the different code designations the cards are to be sorted to. From these contacts the circuit then passes to the code selector switch 310 which may be positioned to cause the decoding of data from either a 45-column or 90-column card. In Fig. 26 this switch is shown in the 90-column position. From there the circuit passes to the electro-magnets controlling the stop pawls. In order to provide the machine with direct current, a rectifier 271 is provided between the source of current and operating circuits of the machine.

Each of the contacts 114 mentioned above is in circuit with a magnet which controls one of the latch pawls 190-196, inclusive. There are seven of these magnets 300-306, inclusive, and they are mounted on plate 157 as shown in Fig. 16. Secured to the armature of each magnet is an arm 224 which, as described above, actuates the associated latch pawl.

A detail description of the circuits involved in the operation of the machine, when a "3" in the upper zone of a 90-column card is sensed, will now be given. A stack of cards is placed in the card magazine 20 and the push buttons 312 are operated in accordance with the digit or digits to be sorted to. After the sensing carriage is positioned over the correct column, the starting button 308 is operated, closing contacts 315 and 316 to close the following circuits. One side of 55 generator 317 through rectifier 271, negative terminal 318, contact 315 of switch 308, terminal 319, conductor 320, winding of relay 321, conductor 322 to the positive terminal 325 of the rectifier operating relay 321 which closes three 60 circuits through its contacts.

(1) From rectifier 271, over conductor 323, through motor 18, conductor 324, contact 326 of relay 321, conductor 327, back to the rectifier 271, thereby operating motor 18.

(2) From positive terminal 325 of the rectifier, conductor 328, winding of relay 329, conductor 330, contact 333 of relay 321, resistance 334, conductor 335 to the negative terminal 318, of the rectifier thus operating relay 329.

(3) A holding circuit for relay 321 is established from negative terminal 318, conductors 335 and 336, contact 337 of relay 321, conductor 338, plug 136, card presence contact 134, plug 136, conductor 339, contact 259 and conductor 75

340, stop switch 341, conductor 342, terminal 319, conductor 320 winding at relay 321 to positive terminal 325, over conductor 322. This circuit holds relay 321 operated until any one of three conditions arise such as no card in the machine which causes the opening at contact 134, a full card pocket or incorrect feeding of cards which opens contact 259; or the stop switch 341 is operated.

10 It is therefore apparent from the above that the operation of relay 321 maintains the power circuit for motor 18 and holds relay 329 operated. The operation of relay 329 closes its contact 343 which prepares a circuit to connect negative current from terminal 318 over conductor 344, contact 345, conductor 346, contact 223, conductor 346, which is common to all of the magnets 300—306 inclusive. The contact 223, however, is not closed until the permutation bars are restored. A condenser 347 is provided across the winding of relay 329 to hold the relay operated for a short interval of time after its operating circuit is opened.

25 From the above it is apparent that the operation of the starting button 308 causes the operation of relays 321 and 329 which through their contacts close the motor circuit and connect negative current to the magnets 300—306 under control of the card presence contact 134, card feed and card pocket contact 259 and restoring pawl contact 223.

30 To illustrate the circuits used for operating the magnets under control of the contacts 114 an example will be given. If a digit "3" has been sensed in the upper zone of a 90 column card 296 (Fig. 25) the hole 314 will cause the third pin 110 from the left (Fig. 6) to descend and close contact 114j which will close a circuit from the common negative potential on conductor 346, winding of magnet 304, conductor 348, contact 349 of the decoding switch 310, conductor 350, contact 351 of the selector button 312, conductor 352, through contact 114j to the common positive potential conductor 353 which extends to positive terminal 325.

35 If the digit "3" had been sensed in the lower zone of a 90 column card the fourth pin 110 from the right (Fig. 6) would enter perforation 354 in card 296 Fig. 25 and contact 114d would be closed completing (1) a circuit from positive conductor 353, right hand set of springs of contact 114d over conductor 355, contact 356 of buttons 312, conductor 357, contact 358 of switch 310, over conductor 348 to negative potential on common conductor 346 through the winding of magnet 302 which operates releasing latch 192; (2) a circuit from positive potential common conductor 353 left hand set of springs of contact 114d conductor 359, contact 360 of buttons 312, conductor 361 to contact 362 which is open due to the switch 310 being in the 90 column position, i. e., with the right hand contacts closed therefore this circuit is not effective at this time.

40 If however the switch 310 had been in the right hand position and the digit "6" in the 45 column code was sensed which is represented by perforation 294 in card 283 (Fig. 24); then the contact 114d will close a circuit from positive potential, common conductor 353 left hand springs of contact 114d, conductor 359, contact 360 of buttons 312, conductor 361, contacts 362, which are now closed, conductor 363 to common negative conductor 346 through the winding of magnet 300. A second circuit is also closed from positive conductor 353, right hand springs of

5 contact 114d, conductor 355 contact 356 of buttons 312, conductor 357, contact 365, conductor 366 to common negative conductor 346 through the winding of magnet 305 which operates and releases pawl 195.

10 In the 90 column code the even digits are represented by an odd digit and a nine, i. e., digit "4" in the upper zone is represented by the "3" perforation 367 and the "9" perforation 368. These perforations will cause the operation of two pins 110 which will close contacts 114j and 114g. The circuit through 114j has already been traced above and cause the operation of magnet 304. Contact 114g closes a circuit from positive conductor 353, through the contact, conductor 369, contact 370 of buttons 312, conductor 371, contact 372, of switch 310, conductor 363 to common negative conductor 346 through the winding of magnet 300 operating it and releasing latch 191.

15 If this "4" in the upper 90 column code is compared with the circuit for the digit "4" in the 45 column code it will be seen that the same relays are operated thereby routing the cards to the same pocket. The digit "4" in the 45 column code represented by perforation 373 will close contact 114j which in turn closes two circuits (1) from common positive conductor 353, right hand springs of contact 114j, conductor 374, contact 375 of buttons 312, conductor 376, contact 377 of switch 310, conductor 348, to common negative conductor 346 through magnet 304; (2) from common positive conductor 353, left hand springs of contact 114j, conductor 378, contact 379 of buttons 312, conductor 380, contact 381 of switch 310, conductor 363, to common negative conductor 346 through magnet 300, operating latch 190. These two magnets are the same as those operated above.

40 Cycle of operations

45 The timing diagram in Fig. 27 shows one complete cycle of the main shaft 30. From 0° to 120° a card is fed by the card picker 21. It is then picked up by the feed rolls 40 and reaches the sensing position at about 307° here it is held by the card stop 60. The cam 146 starts the sensing pins 110 down at 285° and they reach the maximum degree of travel at 350°. The sensing pins remain in their lowest or sensing position until 60° of the following cycle of the machine when they are slowly restored until they reach normal at 110° of the second cycle. The sensing contacts 114 are closed from 310° to 70° of the second cycle. At 100° of the second cycle 55 the card stop 60 raises and the card is fed out of the sensing chamber by rolls 50. It will be noted that the card picker is at the same time feeding a second card into the sensing chamber. The two cards are approximately 20° apart. If 60 this distance is not maintained the card presence feeler arm 253 raises as described above thereby opening the contact 259 thus stopping the machine.

65 The card reaches the chute blade tips 239 at 175° of the second cycle. Prior to this time the chute blades have been selected and raised. To insure this, contact 223 will be closed by cam 214 at 310° of the first cycle. It will be opened again after 118° or 68° of the second cycle which 70 is just prior to the time the sensing contacts 114 are opened, thus preventing the arcing of the contacts as the circuits to the magnets 300—306 inclusive have been opened by contact 223.

75 The restoring of the permutation bars 170—75

177 takes place from 260° to 340° of the previous cycle and are held locked up to 5° of the first cycle. During this time certain of the magnets 300—306 have been operated releasing their associated permutation bars which follow the restoring latch 189. The latch starts to return to normal at 5° and is completely normal at about 90°. At this time levers 186 are released by their respective cams 231 to permit arms 185 to enter between teeth of the permutation bars. The levers 186 become fully effective at 160° of the second cycle and remain so until 195° of that cycle. Upon becoming effective the levers 186 raise the blade operating fingers such as 232 which hold the blades raised until the card has time to enter between them. At 195° of the second cycle the fingers are withdrawn to permit passage of the card which does not reach the location of the fingers until 235° of the second cycle.

20 While there are above described but a limited number of (or one) embodiments of the invention, it is possible to produce still other embodiments without departure from the inventive concept above disclosed, and it is, therefore, desired that only such limitations shall be imposed on the appended claims as are stated therein, or required by the prior art.

What I claim as new, and desire to secure by Letters Patent, is:

30 1. In a sorting machine for record cards having index point positions, a sensing mechanism adapted to sense said index point positions, a distributing mechanism including a plurality of sorting blades, an actuating member individual to each of said blades acting in the path of said cards, a card stop for holding said cards in the sensing mechanism, and means for insuring the withdrawal of said actuating members prior to a card reaching said members, said means also actuating said card stop to hold the following card in the sensing chamber.

40 2. In a sorting machine for record cards having index point positions, a sensing mechanism, a distributing mechanism including a plurality of sorting blades, an actuating member individual to each of said blades, a plurality of permutation bars said actuating members being controlled by said bars, a plurality of pawl members for selectively controlling the movement of certain of said bars from a position of rest to one of two operative positions, and means controlled by said sensing mechanism for selectively operating said pawl members.

50 3. In a sorting machine for record cards, a sensing head comprising a frame pivotally mounted on said machine, a carriage adjustably mounted on said frame carrying a plurality of sensing pins, said carriage being adjustable laterally of said frame by a screw member, a bail

member adapted to disable said pins, a cam for actuating said bail member, and means under control of said cam for locking said screw member from rotation when any of said sensing pins is in operative position.

5 4. In a sorting machine for record cards, a sensing head comprising a frame pivotally mounted on said machine, a carriage adjustably mounted on said frame carrying a plurality of sensing pins, said carriage being adjustable laterally of said frame by a screw member, a bail member adapted to disable said pins, a cam for actuating said bail member, and means under control of said cam for locking said screw member from rotation when any of said sensing pins 10 is lowered.

10 5. In a sorting machine for record cards having index point positions, a sensing head comprising a frame pivotally mounted on said machine, a carriage mounted for lateral adjustment 15 on said frame by a screw member, said carriage carrying a plurality of sensing pins, and means associated with said screw member for locking said pins against movement when said carriage is positioned with the pins between index positions.

20 6. In a sorting machine for record cards, a sensing head comprising a frame mounted on said machine, a carriage adjustably mounted on said frame carrying a plurality of sensing pins, 30 a member adapted to adjustably position said carriage on said frame, a pin disabling means, and means under control of said disabling means for locking said member against movement when any of said sensing pins is in effective position. 35

7. In a sorting machine for record cards, a sensing head comprising a frame pivotally mounted on said machine, a carriage adjustably mounted on said frame carrying a plurality of sensing pins, said carriage being adjustable laterally of said frame by a screw member, a bail member adapted to elevate said pins to ineffective position, a cam for actuating said bail member, and means actuated by said bail for locking said screw member against rotation when said 40 pins are in effective position.

45 8. In a sorting machine for record cards having index point positions, a sensing mechanism, a distributing mechanism including a plurality of sorting blades, a plurality of permutation bars 50 under control of said sensing mechanism, adapted to selectively position said distributing mechanism, a block having a stepped surface thereon acting as a limit stop, and means under control of any one of a certain group of said bars for 55 preventing said bars of said group from limiting on the stop, whereby said bars are selectively positioned.

PAUL MANSEL. 60
